Addison, D. Barrett,

UNITED STATES PATENT OFFICE.

ADDISON D. BARRETT, OF NORFOLK, VIRGINIA.

VULCANIZING APPARATUS.

SPECIFICATION forming part of Letters Patent No. 507,980, dated November 7, 1893.

Application filed December 23, 1892. Serial No. 456,196. (No model.)

To all whom it may concern:

Be it known that I, ADDISON D. BARRETT, a citizen of the United States, residing in the city of Norfolk, in the State of Virginia, have 5 invented certain new and useful Improvements in Vulcanizing Apparatus, of which the following is a specification.

My invention relates to improvements in dental vulcanizing flasks, and more particularly to clamps for connecting the sections of such flasks together; and it has for its general object to provide such a clamp of a peculiar and advantageous construction and one adapted to exert an equable and yielding 15 pressure upon the sections so as to prevent cracking of the plate and insure the perfect formation of the same.

With the foregoing end in view, the invention will be fully understood from the following description and claims when taken in connection with the annexed drawings, in which—

Figure 1, is a perspective view of a flask embodying my invention, and Fig. 2 is a vertical, diametrical section of the same.

Referring by letter to said drawings:—G, indicates the vulcanizing flask, which is designed to receive the plaster mold by which the rubber plate is formed. This flask is 30 preferably of a general circular form and is provided at its middle in the manner illustrated; and it comprises the lower section f, provided at diametrically opposite points with the seats or sockets g; the upper section f', having the depending projections or lugs h, adapted to take into the seats or sockets g, and guide the section f', in its downward movement; and the circular cover H, which is preferably provided with a depending flange, and with a central opening j; such central opening being adapted to permit the escape of the surplus plaster in order that the teeth may be more securely fixed in the plate.

45 A, indicates the main frame of the clamp which is preferably made of two pieces of metal A', C, as illustrated. The piece or section A', which is preferably formed from steel is bent into a general bail shape as shown, 50 and it has its portion k, which rests beneath the flask, of a greater width than its branches

l, which take up alongside the flask and are connected to the piece C, in order to form a broad support for the flask.

B, indicates the screw through the medium 55 of which pressure is exerted upon the sections of the flask so as to move the same together. This screw B, takes through a vertically-disposed, threaded aperture in the section C, of the frame A, and it has its lower 60 portion reduced at m, in order to afford a shoulder n, to bear upon the springs D, which are preferably formed from spring steel and are secured upon the reduced portion m, by a pin p, or in any other approved manner. 65

As better shown in Fig. 1, the springs D, are of a concavo-convex form and of a length approximating the diameter of the flask; and they are disposed at right angles to each other and engage the cover H, only at points 70 adjacent to the edge or periphery thereof, whereby it will be seen that when the screw B, is turned downwardly to exert a pressure upon the flask, such pressure by reason of the springs, will be made yielding and will be 75 equally distributed over the surface of the cover H, so that all sides of the section f', and the cover will be simultaneously moved downward when the rubber is caused to run or move by the heat of the vulcanizing oven. 80 Thus the objectionable cracking of the plate, heretofore caused by first screwing down one side of the upper section and then the other, is obviated, and the formation of a perfect plate insured, which is a desideratum. 85

In order to hold the springs D, in their positions at right angles to each other, I have provided the link or brace E, illustrated in Fig. 1. This link or brace is preferably formed from a light piece of metal and it has 90 its ends connected in any preferred manner to the springs D, adjacent to the outer ends of the same, so as to securely hold them apart.

It will be noted from the foregoing description taken in connection with the drawings that all of the parts of my improved device are durable and practical; and it will also be noted that by reason of the peculiar construction set forth, a strong though yielding pressure on the flask, is secured, which is desirable in this class of devices. 95 100

Having described my invention, what I claim is—

1. In a vulcanizing apparatus, the combination with a sectional flask; of a clamp frame 5 surrounding the same, a pressure screw bearing in said frame, and two concavo-convex springs connected to the screw and disposed at right angles to each other; the said springs being adapted to engage the top of the flask 10 at points adjacent to the edge or periphery thereof, substantially as and for the purpose set forth.
2. In a vulcanizing apparatus, the combination with a flask comprising the lower section f , having the seats or sockets g , the up- 15

per section f' , having the depending projections or lugs h , adapted to engage the seats or sockets of the lower section, and the cover H having the central aperture j ; of the clamp frame, a pressure screw bearing in said frame, 20 and two concavo-convex springs connected to the screw and disposed at right angles to each other; the said springs being adapted to engage the cover H , at points adjacent to the edge thereof, all substantially as and for the 25 purpose set forth.

ADDISON D. BARRETT.
